UNITED STATES PATENT OFFICE.

JOHN A. WEAVER, OF GREELEY, COLORADO.

BEET-TOPPER.

1,075,884.

Specification of Letters Patent. Patented Oct. 14, 1913.

Application filed August 7, 1912. Serial No. 718,712.

To all whom it may concern:

Be it known that I, JOHN A. WEAVER, citizen of the United States, residing at Greeley, county of Weld, and State of Colorado, 5 have invented certain new and useful Improvements in Beet-Toppers; and I do declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention relates to improvements in beet toppers, my object being to provide a construction which shall automatically regulate the position of the knife when performing the beet-topping function so that the 20 tops shall be removed in any predetermined plane below the shoulder of the beet. This is a very important feature. In many machines heretofore proposed for this purpose, the topping function is performed while the 25 beet is in the ground, which has been found to be impractical, for the reason that the beets extend above the surface of the ground varying distances, which makes it impossible to properly regulate the knife to 30 perform the topping function in a uniform plane below the shoulder of the beet.

In connection with my improved beet-topping mechanism it is essential that the beets be uprooted and carried to the knife 35 in such a manner that the shoulder of the beet is exposed to the knife. I prefer to employ the mechanism set forth in my previous application, Serial No. 704,361, filed June 18, 1912. In this construction, 40 which is illustrated in the drawings, the beets are first uprooted and carried upwardly by the uprooting mechanism until they are in position to be engaged by two endless conveyers, the upper conveyer consisting of two endless belts whose innermost 45 runs grasp the tops of the beets, while their bodies are acted upon by a lower conveyer equipped with flights for the purpose, the said flights acting on the beets in opposition 50 to the engagement of the knife and offering the necessary resistance to allow the knife to properly perform the topping function.

In order that the beet may be presented to the knife so that the latter shall remove 55 the top in a uniform plane below the shoul-

der, I employ two rods which are pivotally connected with the frame of the structure at their lower extremities, the said rods being adapted to engage the shoulders of the beets as they approach the knife. The upper extremities of the rods are connected with keepers which are vertically adjustable, the keepers being arranged to raise and lower the knife as the rods are oscillated, the rods being so arranged that they engage the 60 shoulder of the beet on opposite sides of the top whereby the rods are lifted as the beet is carried along by the two conveyers. The keepers which support the knife are originally adjusted to hold the knife in the desired 65 position with reference to the rods. In other words the keepers are adjusted to support the knife as far below the rods as it is desired to remove the top of the beet below the shoulder of the latter. It will 70 thus be seen that the topping by the use of this construction may be accurately and automatically accomplished since the rods bear upon the shoulder of the beet and the knife is supported below the rods, the keepers being 75 lifted as the shoulders of the beets engage the rods during their upward travel under the influence of the two conveyers.

It is important that an apparatus be employed in connection with my improved 80 toppler, of such character that the tops of the beets shall be supported above the shoulder and out of the plane of the knife, in order to prevent possible clogging of the knife due to the interference of the tops. 85 My improved construction set forth in my aforesaid application is specially adapted for use with the automatic topping mechanism, since the endless belts support the tops or foliage of the beets in the desired manner.

Having briefly outlined my improved construction, I will proceed to describe the same in detail, reference being made to the accompanying drawing, in which is illustrated 90 an embodiment thereof.

In this drawing:—Figure 1 is a central vertical section of a beet harvester construction suitable for use with my improved topping mechanism, the latter being shown in 95 end elevation. Fig. 2 is a top plan view of the upper part of the machine, or a view looking in the direction of arrow 2, Fig. 1. Fig. 3 is a section taken on the line 3—3, Fig. 2, viewed in the direction of the arrows, 100

the parts being shown on a larger scale. Fig. 4 is a fragmentary view similar to the rear part of Fig. 1, but showing the topping mechanism in its normal position, or when not engaged by a beet. Fig. 5 is a detail view of one of the keepers upon which the supports for the topping knife are mounted. Fig. 6 is a sectional view upon the line 6—6, Fig. 5.

10 The same reference characters indicate the same parts in all the views.

Let the numeral 5 designate the framework of a beet harvester, the said framework being mounted upon front and rear axles 6 and 7, the latter being supported by front and rear ground wheels 8 and 9. Supported upon the front part of this framework are diggers, or uprooting means, consisting of two plows 10, one only being disclosed in the drawing. These plows are supported on a frame 12 which is vertically adjustable by means of a screw 13 threaded in a nut 14 suitably mounted on the framework of the structure. Two endless belts 16 are arranged to grasp the tops of the beets as they leave the plows, devices 15 being arranged on opposite sides of the beets for lifting the foliage above the shoulders of the beets and holding the foliage in proper position to be engaged by the said belts as they leave the uprooting mechanism. These belts engage rollers 17 at their lower extremities and pulleys 18 at their upper extremities, the rollers and pulleys being journaled in a U-shaped frame-work 19 composed of parallel side members 20 connected at their upper extremities by a transverse member 2. The belts occupy an inclined position, the supporting frame 19 having its forward extremity lowermost and gradually rising as it extends rearwardly. The inner runs 21 of the belts are acted on by suitable devices, as rollers 22, which give the said runs the necessary resistance to cause them to tightly grasp the foliage as the beets are carried upwardly.

Arranged below the belt conveyer is a chain conveyer 23, the same being mounted on sprocket wheels 24 and 25 carried by shafts 26 and 27. This chain conveyer is equipped with flights 28 which act upon the lower parts of the beets whereby the belt conveyers are aided in carrying the beets upwardly to the knife 29, which is supported in a plane between the two conveyers. These conveyers are operated from the rear axle of the machine, the latter being equipped with a gear 30 meshing with a gear 31 fast on a shaft 32 carrying a bevel gear 33 meshing with a smaller gear 34 fast on a shaft 35 whose upper extremity is equipped with a gear 36 meshing with two gears 37 and 38, (see Fig. 2). From the gear 37 motion is communicated to a sprocket wheel 39 connected by means of a

chain 40 with a sprocket 41 fast on a shaft 42 to which is made fast one of the belt-supporting pulleys 18.

It will be understood by an inspection of Fig. 2 of the drawing that the operating mechanism for each belt 16 is the same on both sides of the machine.

Motion is communicated to the chain conveyer 23 from the shaft 32 which carries a sprocket wheel 43 which is connected by a chain 44 in operative relation with the shaft 27 for operating the conveyer 23. As this mechanism is precisely the same as set forth in my previous application, it is not considered necessary to explain the general construction of the machine in extreme detail, and for such detailed explanation, reference is made to the said application.

From the gear 38, which is mounted on a short shaft 45, reciprocating motion is communicated to the knife 29 by means of a crank 46 connected with a shaft 45, and a pitman 47 connected with the said crank at one extremity, its opposite extremity being connected with the knife 29. The opposite extremity of this knife is connected with a spiral spring 49.

The mechanism for automatically regulating the position of the knife by the upward movement of the beets will now be described. The bar 50 of the knife is supported by two arms 51 which are arranged on opposite sides of the topping member 52, which has a saw-tooth edge. These arms are slotted to receive the bar of the knife and their rear extremities are vertically adjustable on keepers 53, the latter having perforated ears 54. Through the ears of each keeper passes a stem 55 whose lower extremity is bent approximately at right angles to its body portion as shown at 56, this bent end being pivotally connected as shown at 57 with a rigid arm 58 secured to the frame-work 19 as shown at 59. The mechanism just described is duplicated on both sides of the two inner runs of the endless belts. Connected with each keeper 53 is the upper extremity of a rod 60 whose lower extremity is pivotally connected, as shown at 61, with a member 62 of an angle bracket 63, the latter being secured as shown at 64 to one of the parallel parts 20 of the frame 19. The bracket arms 62 extend inwardly from the parallel members 20 of the frame and approach the inner runs 21 of the belts quite closely in order that the rods 60 may be in position to engage the shoulders of the beets on opposite sides of the tops as the beets are carried upwardly by the conveyers.

In order that the mechanism which supports the knife may not interfere with the upward travel of the beets, the keepers 53 are sufficiently separated for the purpose, requiring that the upper portions of the rods shall be bent outwardly as shown at 65,

where they are connected with the keepers. The upper extremities of the rods are pivotally connected with the keepers while the stems 55 are pivotally connected with the 5 lower extremities of the standards 58, as heretofore explained, hence as the rods 60 are arranged in the path of the shoulders of the beets as they are carried upwardly by the two conveyers, and in a position intermediate 10 the conveyers, as the beets pass upwardly their shoulders will engage the rods and lift the latter, at the same time raising the knife whose plane has been properly adjusted with reference to the rods. Hence 15 as the beets continue to move upwardly their tops are cut off at the same distance below the top of the shoulders that the knife is located below the rods; and since the arms 20 which engage the bar of the knife are vertically adjustable on the keepers, it will be understood that the tops of the beets may be removed in any desired plane below their shoulders. It will also be understood that the beets themselves, as they travel upwardly, serve to automatically regulate the 25 position of the knife for topping purposes. The knife-bar-engaging arms 51 are vertically adjustable on the keepers 53 by means of set bolts 66, or in any other suitable 30 manner.

From the foregoing description, the use and operation of my improved beet topper will be readily understood. As the machine is drawn across the field, the row of beets 35 is uprooted by the plows 10, the foliage being simultaneously lifted by the devices 15. As the beets leave the plows, their tops are engaged by the inner runs 21 of the two belts, while the lower parts of their bodies 40 are acted on by the chain conveyer 23, the two conveyers thus carrying the beets upwardly, their bodies being supported in positions at right angles to the planes of the conveyers' travel. As the rods 60 are properly 45 arranged to engage the shoulders of the beets on opposite sides of their tops, or foliage, the beets will lift the rods whereby the knife is brought into the proper plane for severing the tops. As soon as the topping 50 function has been performed the beets are released by the chain conveyer and dropped downwardly into a suitable receptacle 67, while their tops are carried upwardly by the belt conveyer, and dropped upon a sort 55 of apron 68 secured to the upper part of the frame-work, whereby the tops are dis-

charged at the rear extremity of the machine, and not allowed to interfere with any of the mechanism thereof.

Having thus described my invention, what I claim is:

1. The combination of uprooting means, a knife, means for carrying the uprooted beets to the knife for topping purposes, and means for automatically regulating the 65 knife to bring it into position to remove the top in a predetermined position with reference to the shoulder of the beet, said means comprising upright stems pivotally mounted, keepers vertically slideable on the stems 70 and forming a support for the knife, and rods extending forwardly from the keepers into the path of the beets as the latter approach the knife.

2. The combination of uprooting means, a 75 knife, means for carrying the uprooted beets to the knife for topping purposes, means for automatically regulating the knife to bring it into position to remove the top in a predetermined position with reference to 80 the shoulder of the beet, said means comprising upright stems, pivotally mounted, keepers vertically slideable on the stems, a knife support vertically adjustable on said 85 keepers, and rods extending forwardly from the keepers into the path of the beets, as the latter approach the knife.

3. In combination, a beet conveyer arranged to hold beets in a predetermined position, a slideable keeper, a support adjustable 90 in said keeper, a knife mounted in said support, and bearing rods adapted to be acted upon by the shoulders of the beets as the latter are moved by the conveyer for shifting the keeper to cause the knife to act upon 95 the beets at the proper height.

4. In combination, a beet conveyer arranged to hold the beets in a predetermined position, slideable keepers, supports adjustable in said keepers, a reciprocating knife 100 mounted in said supports and bearing rods adapted to be acted on by the shoulders of the beets as the latter are moved by the conveyer for shifting the keepers to cause the knife to act upon the beets at the proper 105 height.

In testimony whereof I affix my signature in presence of two witnesses.

JOHN A. WEAVER.
